CLAIM

The ornamental design for the athletic court grid sur-
face tile, as shown and described.

DESCRIPTION

FIG. 1 is a top plan view of an athletic court grid sur-
face tile showing my new design;

FIG. 2 is an edge elevational view thereof;

FIG. 3 is a right side elevational view thereof;

FIG. 4 is a bottom plan view thereof;

FIG. 5 is an enlarged top fragmentary view of the cor-
ner portion thereof; and,

FIG. 6 is an enlarged bottom fragmentary view of the
corner portion thereof.
